UNITED STATES PATENT OFFICE

VINCENT TANASSO, OF NEW YORK, AND JACOB J. POMERANZ, OF BROOKLYN, NEW YORK

DESIGN FOR BAR MATERIAL FOR OPHTHALMIC MOUNTINGS

Application filed April 17, 1931. Serial No. 39,539. Term of patent 14 years.

To all whom it may concern:

Be it known that we, VINCENT TANASSO and JACOB J. POMERANZ, citizens of the United States, and residents, respectively, of the city of New York, borough of Bronx, in the county of Bronx and State of New York, and of the city of New York, borough of Brooklyn, in the county of Kings and State of New York, have invented the new, original, and ornamental Design for Bar Material for Ophthalmic Mountings, of which the following is a specification.

Figure 1 is a segment of bar material for ophthalmic mountings showing our new design.

Figure 2 is an edge view thereof.

We claim:

The ornamental design for bar material for ophthalmic mountings substantially as shown.

VINCENT TANASSO.
JACOB J. POMERANZ.
